TOY SKI JUMPER

Kermit Graetz, Verona, N. J.

Application October 17, 1945, Serial No. 622,747

4 Claims. (Cl. 46—130)

1

My present invention relates to figure toys and is directed more particularly to a toy ski jumper.

One of the objects of my invention is to provide a realistic toy ski jumper of novel construction which simulates the movements of a skilled human ski jumper.

Another object of my invention resides in a toy ski jumper in which a toy figure is caused to perform a somersault during its movement down a ski-track-like structure.

A further object of the invention constitutes the designing of a toy figure which is so constructed and balanced as to simulate effectively the movements of a skilled human ski jumper.

A still further object of the invention is to provide an interesting, amusing and novel toy of simple and inexpensive design.

In the accompanying drawing:

Figure 1 shows, in perspective, the major portion of a toy responding to the present invention;

Figure 2 is a vertical medial sectional view taken longitudinally through Figure 1;

Figure 3 illustrates the toy ski jumper figure by itself and

Figure 4 is an enlarged fragmentary view of the toy ski jumper and the contiguous portion of the ski track, partly in section and partly in elevation.

Like numerals designate corresponding parts throughout the various views of the drawing.

Referring to the drawing in detail, the numeral 10 indicates an elongated base member on which is mounted a main body member 11, a portion of the upper edge of which is formed as a ski track 12 which is a smooth steeply sloping surface and another portion of which is cut away to form a free space within which the gyrations of the toy ski jumper occur. Beyond the free space, the member 11 again slopes steeply downwardly at 12' for a purpose to be herein-after set forth.

The member 11 is disposed between a pair of vertical wall-like members 13 the upper edges of which parallel ski track 12 but project somewhat thereabove, as shown, to form guide rails which prevent the toy ski jumper from moving laterally and thus leaving the track. The lowermost portions of the upper edges of the member 13 merge into a flattened concave section which define and constitute lateral boundaries for the free space above referred to. The member 13 terminates short of the sloping portion 12' as shown.

The member 14 serves as a ski run and is preferably composed of a strip of flexible linoleum

2

or the like with a polished or glossy upper surface. One end of the member 14 has an aperture 15 through which stud 16 passes. The stud projects from the upper part of sloping portion 12' and the member 14 can thus be disassembled for packing, storing and shipping purposes, if desired. The end of the member 14 may be reinforced by a cross-piece 17 which serves to maintain the member in the proper position illustrated.

The toy ski jumper comprises a figure 18 mounted on a member 19 shaped to the general configuration of a pair of skis and narrower than the clearance between the member 13. The formed portions of member 19 are provided on their underside with feet 20 which have smooth rounded bottoms adapted to slide along ski track 12 and ski run 14. A cross bar 21 of round section is rigidly secured to the upper surface of member 19 in the position illustrated. In other words, the figure 18 which is configured to resemble a skier is mounted on a member having a central platform with forwardly and rearwardly projecting parallel ski-like extensions.

It is to be understood that the ski jumper is so constructed, balanced and proportioned as to enable it effectively to follow the gyrations indicated in Figure 2 from which it will be observed that the toy figure somersaults in the free space beyond the end of the ski track and lands in skiing position on the ski run down which it proceeds. Thus, the toy figure slides down ski track 12 with cross bar 21 above the guide rails until it enters the free space at which time it drops down until cross bar 21 strikes the top edges of members 13, whereupon, due to the balancing of the toy figure, the figure 18 goes through a clockwise rotation and cross bar 21 rolls accordingly until the toy ski jumper assumes the dotted line position A from which it drops onto ski run 14 and slides down the same.

It is to be understood that the parts described and illustrated may be made of any suitable material including wood, metals, alloys and plastic materials. The toy is preferably but not necessarily finished in colors simulating the actual appearance of the true counterparts. The sizes and proportions of the various parts are subject to modification depending upon the materials employed and the weight and density of such materials. Such variations are all deemed to be a part of my present invention which is rather that defined by the appended claims.

Moreover, the feet 20 may be omitted and if desired the member 19 may have projections cor-

responding to the ends of the cross bar 21 but formed in one piece with said member, all within the spirit and scope of the invention.

I claim:

1. A toy of the character described comprising a downwardly sloping track and a toy figure capable of sliding movement down said track actuated by gravity to simulate performance of a somersault at the lower end of said track and a run over which said figure is movable from said track.

2. A toy of the character described comprising a downwardly sloping track, guide rails projecting above and downwardly beyond said track, forming a free space below the lower end of the track, and a toy figure having portions capable of sliding down the track and having lateral projections cooperating with said guide rails and related to the center of gravity of said member so as to cause the toy figure to perform a somersault in said free space.

3. A toy of the character described comprising a downwardly sloping track, guide rails projecting

above and downwardly beyond said track, forming a free space, and a toy figure having portions capable of sliding down the track and having lateral projections cooperating with said guide rails and related to the center of gravity of said member so as to cause the toy figure to perform a somersault in said free space, and a downwardly sloping run beyond said lower ends of said guide rails to receive said toy figure after it has performed said somersault.

4. A toy of the character described comprising a main body member provided with a ski track and cut away below said ski track, a pair of vertical members between which the main body member is disposed which rise above such main body member to form guide rails and to define a free space beyond and below said ski track, a steeply sloping surface on said main body member beyond said vertical members and said free space and a flexible member secured to the steeply sloping surface and forming a ski run.

KERMIT GRAETZ.
